US0D1077209S

(12) United States Design Patent (10) Patent No.: US D1,077,209 S
(45) Date of Patent: * May 27, 2025

(54) ORAL IRRIGATOR

(71) Applicant: Touchstone Ego LLC, Plano, TX (US)

(72) Inventor: Xuemei Fang, Jiangxi (CN)

(73) Assignee: Touchstone Ego LLC, Plano, TX (US)

() Term: 15 Years

(21) Appl. No.: 29/977,208

(22) Filed: Dec. 6, 2024

(51) LOC (15) Cl. 28-03

(52) U.S. Cl.

USPC D24/111; D24/152

(58) Field of Classification Search

USPC D24/111, 108, 110, 152, 176; D4/100, D4/101, 110, 111

CPC ... A61C 15/046; A61C 15/047; A61C 15/048; A61C 17/00; A61C 17/005; A61C 17/02; A61C 17/0202; A61C 17/0205; A61C 17/0211; A61C 17/16; A61C 17/20; A61C 17/22; A61C 17/222; A61C 17/225; A61C 17/227; A61C 17/32; A61C 17/34; A61C 17/36

(57) CLAIM

The ornamental design for an oral irrigator, as shown and described.

DESCRIPTION

FIG. 1 is a perspective view of an oral irrigator showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is an enlarged top plan view thereof; and,

FIG. 8 is an enlarged bottom plan view thereof.

The broken lines depict portions of the oral irrigator that form no part of the claimed design.

1 Claim, 8 Drawing Sheets
